DESIGN FOR AN ANDIRON

Arthur G. Lovejoy, Jr., Malden, Mass.

Application July 26, 1933, Serial No. 48,839

Term of patent 7 years

To all whom it may concern:

Be it known that I, ARTHUR G. LOVEJOY, JR., a citizen of the United States of America, residing at Malden, in the county of Middlesex and State of Massachusetts, have invented a new, original, and ornamental Design for Andirons, of which the following is a specification, reference being had to the accompanying drawing, forming part thereof.

In the accompanying drawing:

Figure 1 is a front elevation of an andiron showing my new design.

Figure 2 is a top plan view of the finial of the andiron shown in Figure 1.

Figure 3 is a side view of the andiron.

What I claim is:—

The ornamental design for an andiron, as shown and described.

Signed by me at Boston, Suffolk County, Massachusetts, this 3 day of July, 1933.

ARTHUR G. LOVEJOY, JR.
